UNITED STATES PATENT OFFICE.

HENRY LEGER, OF BOSTON, MASSACHUSETTS.

MITER-BOX.

1,046,613.

Specification of Letters Patent.

Patented Dec. 10, 1912.

Application filed October 30, 1911. Serial No. 657,514.

To all whom it may concern:

Be it known that I, HENRY LEGER, of Boston, in the county of Suffolk and State of Massachusetts, have invented certain new and useful Improvements in Miter-Boxes, of which the following is a specification:

This invention relates to miter boxes, and more particularly to folding miter boxes.

The object of the invention is to provide 10 a miter box which has a wide range of capacity, which can be adjusted to cut any desired angle, which has provision for cushioning the saw, and which can be folded so as to occupy a comparatively small space.

15 Accordingly, a feature of the invention contemplates the provision of a miter box having a work rest or vertical face-plate adapted to be mounted on a wooden horse or any other suitable support. This work rest 20 may be provided with extensions hinged thereto and adapted to be folded up out of the way for transportation, or lowered to produce a long back or vertical support for the material which is to be sawed.

25 A further feature of the invention contemplates the provision of means for varying the height of the saw, as by a telescoping structure, and this structure may be utilized for pneumatically cushioning the 30 saw.

35 A further feature contemplates the provision of means for securing the saw guide so that any angle can be cut. In its present embodiment means are provided for locking the guide automatically at the more common angles, which locking means can be released by means operated by the saw, and means are also provided for clamping the saw guide in any degree of angularity. 40 Other features of the invention will be referred to in connection with the specific description of the illustrated embodiment of the invention.

45 The several features of the invention will be clearly understood from an inspection of the accompanying drawings and the following detailed description of the construction shown therein.

50 In the drawings Figure 1 is a plan view of the miter box with a saw in position for cutting a board at right angles to its length, Fig. 2 is a side elevation of the same, Fig. 2^a is a fragmentary view of the locking

and tripping mechanism, Fig. 3 is a sectional front elevation taken on the line 3-3 in Fig. 2, Fig. 4 is a side elevation of the miter box in folded position, Fig. 5 is a vertical section taken on the line 5-5 in Fig. 3, showing the telescopic structure in extended position, Fig. 6 is a horizontal section on an enlarged scale taken on the line 6-6 in Fig. 5, Fig. 7 is a fragmentary side elevation of a modified form of saw guide, Fig. 8 is an end elevation of the same, and Fig. 9 is a detail sectional view of the 65 pneumatic cushion controlling device.

As illustrated in the drawings, the device comprises a work rest 10, having a front or work-engaging face formed by the finished faces of ribs 12. The lower edge of the work rest is provided with a finished face 14, which is at right angles to the work-engaging face 12. The work rest is formed with two vertical sections separated by a slot 16 through which the blade 18 of the saw can 75 pass. The vertical sections are joined to an offset bar 20, which also has a finished front face. The offset bar is adapted to be clamped to any suitable support 22, having a flat upper face for engagement by the 80 face 14. This support may be a wooden horse, a plank, a bench, or any other suitable support. The device is clamped to said support by means of hooked screws 24 having laterally projecting fingers 26, 85 which engage the under side of the support 22. The threaded stems of the screws pass through bosses 28 on the rear of the cross-bar and enter nuts 30, which bear against the upper ends of said bosses. Screws 31 90 may be provided, having their ends pointed and projecting below the finished surface 14 to enter the top surface of the support to which the device is attached. By this construction the work-engaging face 12 is 95 held perpendicular to the upper face of the support 22, and this support may be of any desired width to accommodate any desired width of material 23 which is to be cut.

100 In order to provide a long work-engaging face, and yet be able to fold the device into a comparatively small space, a pair of angle arms 32 are pivotally connected by means of screws 34 to the outer ends of the work rest 10. These arms are provided

- with ribs 36; having finished faces which are in the plane of the faces of the ribs 12, thus providing a work-engaging face of considerable extent when the arms are 5 in the full line position shown in Figs. 1, 2 and 3. These arms may be folded as indicated in dotted lines in Fig. 3 and in full lines in Fig. 4 to economize space and facilitate transportation.
- 10 The work rest is provided at its rear with two sockets 40, 42, in which hollow, open-ended plungers 44 and 46, respectively, are mounted to slide. These plungers are fitted in said sockets sufficiently tight to 15 prevent the escape of air therebetween, and are adapted to be held in adjusted position by knurled clamping screws 48. A peripheral groove, 50 is formed in the exterior of each plunger, which is adapted to receive 20 the inwardly projecting ends 52 of a wire spring 54. These springs lie in grooves near the upper ends of the sockets 40, 42, and the ends 52 prevent the accidental withdrawal of the plungers from their sockets, 25 as shown in Fig. 5.

Slidably mounted within the plungers 44 and 46, are plungers 56 and 58, respectively, having their upper ends secured in a cross-bar 60, by means of threaded caps 62. The 30 plungers 56 and 58 fit the plungers 44 and 46 so as to prevent escape of air therebetween, and are adapted to be held in adjusted position by means of screws 64. The plungers 56 and 58 are hollow and are provided with screw threaded plugs 66 in their lower ends, said plugs having a central passage 68. The upper ends of the plungers 56 and 58 are provided with air passages 70 and 72, respectively, which communicate 35 with an air passage 74 extending entirely through the cross-bar 60, and also with similar passages 76, 78, respectively, communicating with the external atmosphere. The passages 76 and 78 are adapted to be 40 controlled by screws 80 and 82, respectively. Thus a pneumatic cushion for the saw is formed within the telescoping structure, which can be controlled by either of the screws 80 or 82. By regulating either of 45 said screws so that there is only a slight air discharge through the corresponding passage, the weight with which the saw bears upon the material being sawed can be regulated so that the latter will not be 50 torn or splintered. Although two regulating screws are shown, it will be understood that only one need be employed. By means of the above telescoping structure, the vertical capacity of the device is greatly increased.

The saw-guiding means comprises an arm 84 pivoted by a screw 86 in a boss on the cross-bar 60. A stud 88 is secured in the arm 84 by a set screw 89, and depends therefrom between the sockets 40 and 42. Said

stud is provided with a slot 90 to receive the blade 18 and the back 19 of the saw, the lower edge of the back being adapted to rest on the shoulders formed in the slot 90. The arm 84 is bifurcated to provide bars 85 and 87, which straddle and are adapted to bear against a sector-shaped web 92, having an arcuate slot 94. A clamping screw 96 on the arm 84 passes through the slot 94 and is adapted to clamp the bars 85 and 87 against the web 92 to hold the saw at any degree of angularity as determined by the protractor 98 mounted adjacent to the slot 94.

Pivoted in ears 100 on the arm 84 is an arm 102, which forms an extension of the arm 84 and carries the front stud of the saw guide. In the embodiment shown in Figs. 1, 2 and 4, thus stud 104 is slotted similarly to the stud 88, and is held removably in the outer end of the arm 102 by a knurled nut 106. The stud 104 is cut away at 108 to clear the end of the bar 87, as shown in Fig. 4. When it is desired to fold up the device, the stud 104 is removed from the outer end of the arm 102, the arm is then swung over into the position shown in Fig. 4, and the stud is inserted as shown in this figure and secured by the nut 106. The head of a screw 110, carried by a plunger 112 to be hereinafter described, projects into the enlarged portion of the saw guiding slot, and when the nut 106 is screwed down tightly to draw the stud up into position, this screw head prevents the arm from swinging upward.

In a modified form, the stud 104 is replaced by a stem 114, pivoted between ears 116 on an arm 118 similar to the arm 102, and clamped by a screw 120.

In order to automatically lock the saw guide in any one of the more common angles, such as 10°, 22.5°, 30°, and 45°, I provide a plunger 112, which is adapted to enter any one of the holes 122 formed in the sector-shaped web 92. A rod 126 is slidably mounted in ears 128 and 130 on the side of the arm 84, and is provided with a laterally projecting finger 132, which is connected to the plunger 112 by the screw 115. The plunger 112 is slidably mounted in a lug 113 projecting upward from the end of the bar 87. A coiled spring 134 embraces the rod 126 and is held between a pin 136 on said rod and the ear 130, thus tending normally to keep the plunger in one of the holes 122, and automatically pushing said plunger into one of said holes whenever the former comes opposite one of the latter.

In order to release the saw guide, I provide a tripping shaft 140, on the side of the bar 102. This shaft is provided at one end with a laterally projecting lug 146, which is adapted to be brought into the path of the 130

opposing end of the rod 126, after the arm 102 has been swung up into the position shown in Fig. 2. This is accomplished by raising the handle of the saw. A knob 148 is provided at the opposite end of said shaft, whereby the latter may be moved manually, but when the arm 102 is swung up into the position indicated in this figure the knob and lug on the shaft cause the latter to rotate partially automatically so that the lug 146 drops into position opposite the end of the rod 126. Then when the saw and the arm are lowered into horizontal position, the lug engages the end of the rod 126 and 15 pushes the latter to draw the plunger 112 from the web 92 and release the arm 84 so that the saw can be swung in any desired direction. When it is desired to release the plunger to lock the arm 84, the knob 148 is grasped and the shaft 140 rotated slightly to swing the lug 146 out of the path of the rod 126, whereupon the plunger is free to enter any one of the holes 122, which it will do as it is brought opposite the same. When 20 it is desired to secure the saw guide at any intermediate point it is clamped by means of the screw 96. When the clamping screw 96 is released and the plunger is held by the tripping shaft with the saw in horizontal 25 position, the latter can be swung to any position within the capacity of the device as indicated by the protractor 98.

While I have illustrated and described a preferred embodiment of the invention, I 30 am aware that many modifications can be made therein by any person skilled in the art without departing from the scope of the invention as expressed in the claims. Therefore I do not wish to be limited to all the 35 details of construction shown and described, but

What I claim is:—

1. A miter box, comprising a vertical work rest, a pair of tubular sockets on the rest, a bar, a pair of plungers depending from the under side of said bar and arranged to slide in said sockets, an arm pivotally mounted on said bar, a pair of saw-guiding studs depending from the under 50 side of said arm, and means for regulating the speed with which the plungers are lowered in said sockets.

2. A miter box, comprising a work rest, an adjustably supported bar carried by the 55 work rest, a jointed arm pivotally mounted on said bar and provided with saw guiding studs, spring actuated means for locking said arm, and means for releasing said arm, said releasing means being operated by swinging one section of the jointed arm relatively to the other upon the joint.

3. A miter box comprising a face plate, a pivotally mounted saw guide, telescoping means for varying the height of the saw 60 comprising an air chamber, and means for

controlling the escape of air from said chamber.

4. A miter box, comprising a work rest, means for securing the rest upon a support, extensions hinged to said rest having their 70 work-engaging faces in the plane of the work-engaging face of said rest, and a pivotally mounted saw guide.

5. A miter box, comprising a work rest, means for securing the rest upon a support, 75 a pivotally mounted saw guide, means comprising a spring pressed plunger for automatically locking said guide, and means operable by the saw for releasing said guide.

6. A miter box, comprising a work rest 80 having two finished surfaces at right angles to one another, a pair of extension members pivotally connected to the ends of said rest and having their work-engaging faces lying in the plane of the work-engaging face of 85 said rest, and a pivotally mounted saw guide.

7. A miter box, comprising a work rest, a pair of tubular sockets, a saw guide, plungers on said saw guide arranged to slide in 90 said sockets, and means for holding said plungers in adjusted position.

8. A miter box, comprising a work rest, a pair of tubular sockets, a saw guide, hollow plungers on said saw guide arranged 95 to slide in said sockets and forming a pneumatic cushion for the saw, and means for regulating the escape of air from said cushion.

9. A miter box, comprising a work rest, 100 extensions pivotally mounted on said work rest which have their work-engaging faces in the same plane, means for clamping the rest upon a support, and a saw guide.

10. A miter box, comprising a work rest, 105 a pivotally mounted saw guide, a plunger for locking said guide, a tripping shaft arranged to release said plunger, and means for clamping the guide in any desired position.

11. A miter box, comprising a work rest, 110 and a folding saw guide provided with a joint intermediate its length, whereby one part may be folded over upon another.

12. A miter box, comprising a work rest, 115 a pair of sockets, a pair of plungers slidably mounted in said sockets, a bar connecting the plungers, an arm pivotally mounted on said bar, a pair of saw guides depending from said arm, and means for securing 120 said arm in adjusted position.

13. A miter box, comprising a work rest, a pair of plungers slidably mounted on said rest, a pivotally mounted arm carried by said plungers, means for locking the arm 125 against rotation, and means operable by the saw for releasing the locking means.

14. A miter box, comprising a work rest, a pair of sockets, a pair of plungers slidably in said sockets and constituting an air 130

cushion, and a pivotally mounted saw guide carried by said plunger.

15. A miter box, comprising a work rest, a saw guide, and telescoping means constituting an air cushion for varying the height of the saw.

16. A miter box, comprising a work rest and a pivotally mounted folding saw guide provided with a joint intermediate its

length, whereby one part may be folded 10 over upon another.

In testimony whereof I have affixed my signature, in presence of two witnesses.

HENRY LEGER.
